ADOLPHUS BROWN AND FELIX BROWN, OF NEW YORK, N. Y.

Letters Patent No. 95,313, dated September 28, 1869.

IMPROVED LUBRICATOR FOR JOURNAL-BOXES.

The Schedule referred to in these Letters Patent and making part of the same.

To all whom it may concern:

Be it known that we, ADOLPHUS BROWN and FELIX BROWN, both of the city, county, and State of New York, have invented a new and improved Lubricator for Journal-Boxes; and we do hereby declare the following to be a full, clear, and exact description thereof, which will enable those skilled in the art to make and use the same, reference being had to the accompanying drawing, forming part of this specification, in which drawing—

Figure 1 represents a longitudinal central section of this invention.

Figure 2 is a transverse section of the same.

Similar letters indicate corresponding parts.

This invention relates to a journal-box in which, by means of certain devices, the surplus oil leaking out at the ends of the journal-box, is carried back to the oil-reservoir by inclined troughs or channels, into which such surplus is received on leaking out at the ends of the journal-box, and the waste-channels extend beyond the ends of the journal-box, so that they overlap a flange or collar, which may be secured to the shaft to keep the same in position, and thereby waste of oil from the adjoining surfaces of the journal-box and collar is prevented.

This object is still further insured by providing the collar with a depression, which prevents the surplus oil from spreading on the surface of the collar, and compels the same to run back into the waste-channel.

A mud-box, which is screwed into the bottom part of the oil-reservoir, serves as a receptacle for the dirt, which otherwise would be liable to accumulate in the oil-can.

In the drawing—

The letter A designates a journal-box, which forms the bearing for the shaft B, and which may be secured to a hanger, or made in any other desirable form or shape.

This journal-box is provided with an oil-reservoir, C, which may be situated in the middle of the box, as shown in the drawing, or which may be situated in any other convenient position.

This reservoir is supplied with oil through a suitable hole in the cover of the journal-box, and the oil is carried up to the journal by means of a chain, D, which is hung loosely on the shaft, and dips into the oil in the reservoir.

By this arrangement the chain D carries up a sufficient quantity of oil to lubricate the shaft whenever the shaft is in motion, and as soon as the motion of the shaft stops, the supply of oil also stops, and no lubricating-material is wasted.

The oil carried up by the chain D, spreads over the entire length of the journal, and it is liable to leak out

at the ends of the journal-box. This surplus oil is carried back to the reservoir C, by means of channels E, which extend from said reservoir toward both ends of the box, (one only being shown in the drawing.)

These waste-channels extend beyond the ends of the journal-box, so that they overlap the adjoining surfaces of said box, and of a collar, F, which may be required to keep the shaft in position, and thereby waste of oil from these adjoining surfaces is prevented.

The collar F is provided with a depression, a, as shown in fig. 1, whereby the surplus oil is prevented from spreading on the surface of said collar, and it is compelled to flow back into the waste-channel.

In the bottom of the oil-reservoir C, is secured a mud-receptacle, G, which serves to collect the mud or sediment that would otherwise be liable to collect at the bottom of the reservoir C, and interfere with the correct operation of the lubricating-mechanism. Said mud-receptacle is fastened to the oil-reservoir by means of a screw-thread or other fastening, so that it can be readily taken off whenever it may be required, for the purpose of cleaning it.

The chain D may also be used with a journal-box of the ordinary construction, by suspending from said box an oil-reservoir, H, and hanging the chain loosely over the shaft, close to the end of the journal-box, as shown in fig. 1.

The reservoir H may also be provided with a mud-receptacle, or it may be constructed in the form of an ordinary trip-cup, and taken off from time to time for the purpose of cleaning.

Having thus described our invention,

What we claim as new, and desire to secure by Letters Patent, is—

1. The inclined channel E, contained from the journal-box A, extending inwardly and upwardly, and beyond the journal-box and the groove a of the collar F, in order to convey the spread oil back to the reservoir C, in the manner substantially as described.

2. The mud-receptacle G, in combination with the oil-reservoir, lifting-chain, and journal-box, substantially as set forth.

3. The waste-channel E, in combination with the oil-reservoir C, lifting-chain D, journal-box A, and shaft B, substantially as described.

4. The depression or cavity a, in the collar F, in combination with the waste-channel E, oil-reservoir C, lifting-chain D, journal-box A, and shaft B, substantially as described.

ADOLPHUS BROWN.
FELIX BROWN.
